YARN TENSIONING DEVICE

Lewis H. Myers, Philadelphia, Pa., assignor to
Provident Trust Company of Philadelphia,
Philadelphia, Pa., a corporation of Pennsylvania, trustee

Application April 26, 1933, Serial No. 667,943

9 Claims. (Cl. 242—154)

This invention relates to yarn tensioning devices for winding machines; and it has reference more particularly to tensioning devices especially advantageous in winding yarns which have been moistened for acquisition of greater pliability so that they may be more readily worked incident to manufacture, for example, of knitted products such as stockings.

In the operation of winding machines ordinarily employed in packaging yarns for use in knitting machinery, the packages are formed by winding the yarns on spindles which revolve at a constant speed. Accordingly therefore during the winding of each package, the linear speed of the yarn increases gradually in direct proportion to the increase in diameter of the growing package. In order to insure even winding and uniform density in the package under these conditions, it is requisite during winding that the restraint upon the yarn be gradually decreased compensatively with the progressively increasing linear speed of said yarn consequent upon the growth of the package. While different forms of tension devices have been devised heretofore which quite satisfactorily accomplish this function incident to winding dry yarns, I have found that they are unsuited to winding yarns which have been moistened or wetted.

The chief aim of my invention is to correct the deficiency to which attention has just been directed, that is to say, its main object is to provide a simple, reliable and efficient device which is readily fitted to standard types of winding machines and which will operate automatically to maintain wet as well as dry yarns under uniform tension irrespective of changes in the linear speed of the yarns incident to winding.

In connection with a tensioning device having the above attributes, it is a further aim of my invention to provide adjustments whereby the device may be adapted for operation upon yarns of different materials and gages, and moreover whereby it may be set to maintain any desired degree of tension on the yarns.

Still other objects and attendant advantages of this invention will be manifest from the detailed description following of the attached drawings, wherein Fig. I shows in end elevation, a typical commercial winding machine known as a universal winder, fitted with my improved automatic tensioning device.

Fig. II is a perspective view of the tension device drawn to a larger scale.

Fig. III is a front elevation of the device likewise drawn to a larger scale; and

Fig. IV shows the device in side elevation or as viewed from the right in Fig. III.

With more detailed reference first more particularly to Fig. I of these illustrations, the numeral 5 designates the housing of the winding machine, which, at the top, affords journal support for a spindle 6 whereon the conical yarn package C is formed. Suitable means (not shown) serve to drive the spindle 6 at a rapid constant speed. Incident to winding, the yarn indicated at Y is directed over a threading bail 7 to a traversing guide 8 on a carriage 9. This carriage 9 is supported by a swinging frame 10 which is fulcrumed at 11 on the housing 5 of the machine, and is reciprocated longitudinally of the spindle 6 by suitable means so that the yarn Y is distributed over the length of the package C by the traversing guide 8 in the well known manner. The swinging frame 10 is counterweighted at 12 so that the traversing guide 8 is yieldingly maintained at all times in contact with the surface of the package C throughout each winding operation also as well understood in the art.

Referring now also to Figs. II, III and IV, it will be observed that my novel tensioning device comprises a bracket plate 13 which is secured, by means of screws 14, to the end of a supporting arm 15 afforded by the winding machine. Enroute from a source of supply (not shown) to the spindle 6, the yarn Y passes through a series of pig-tail guides 16, 17, 18 and 19 on the bracket plate 13. As shown in Fig. IV, the guides 16, 18 and 19 lie in a direct vertical line, while the guide 17 is somewhat offset laterally to determine an angular deviation of the yarn Y at 20. Intermediate the guides 17, 18, the yarn Y passes between a pair of restraining members having the form of circumferentially-rounded disks 21, 22 which are coaxially mounted on a stud 23 fixed, by means of a set screw 24a, in a boss 24 of the bracket plate 13.

In practice, the disk 21 is made of porcelain, and formed, as shown in Figs. II and III, with a forwardly projecting axial neck 25 which is pierced to fit the stud 23. The disk 22, on the other hand, is fashioned to dished configuration from light sheet metal and centrally apertured to freely fit the neck 25 of the disk 21. A conical compression spring 26 yieldingly urges the disk 22 toward the disk 21 so that restraint is imposed upon the yarn Y as it passes between the opposing surfaces of said disks.

Journaled in a bearing 27 of the bracket plate 13 is a transverse rock shaft 28 which has se-

cured to it at its front end, an extensible finger 29. As shown in Fig. III the extensible portion 30 of the finger 29 has its free end downturned to project into a longitudinal slot 31 at the outer end of the stud 23 to constitute a movable abutment for the conical spring 26. The compressive force of the spring 26 may be varied by adjusting the extensible portion 30 of the finger 29, a set screw 32 being provided for this purpose.

10 Pinned to the rock shaft 28 immediately adjacent the front side of the bearing 27 (i. e. at the left of the latter in Fig. IV) is a vertical arm 33. At its outer end the arm 33 carries a porcelain projection 34 for engaging the yarn Y and angularly deflecting it between the pig-tail guides 18, 19 as shown in Figs. I and III. A third arm 35 is secured to the rock shaft 28 immediately adjacent the rear side of the bearing 27 (i. e. the right hand side of the latter in Fig. IV), said arm 20 being angularly set on the shaft and having its outer end bifurcated as at 36 to accommodate a circumferentially grooved roller 37. Within the groove of the roller 37 rests a lever 38 which is freely fulcrumed at 39 to a laterally projecting lug 40 of the bracket plate 13. As shown in Figs. I and III, the lever 38 is engaged by the pierced end 41 of an angularly configured link 42 whereof the opposite end is pivoted at 43 to an extension piece 44 fixedly attached to the weight 12 of the swinging frame 10 of the winding machine. By shifting the block weight indicated at 45 along the lower horizontal portion 42a of the link 42 it is possible to vary the downward pressure exerted by the outer end 41 of said link upon the lever 38.

35 To the inner end of the rock shaft 28 is affixed an eccentrically bored disk weight 46 which may be set in any desired position of angular adjustment by means of a thumb screw 47. The clockwise swing of the rock shaft 28 is limited by a thumb screw 48 which is adjustable in an ear 49 projecting from the bearing 27 and which coacts with the arm 33. A jamb nut 50 with a milled edge is utilized as a convenient means for securing the thumb screw 48 against displacement after adjustment.

40 The operation of my improved tensioning device is as follows:—As the diameter of the package C increases incident to its winding, the counterweighted frame 10 of the winding machine is moved clockwise on its fulcrum axis 11 in the known manner. By virtue of its connection to the swinging frame 10, the link 42 is drawn leftward in Figs. I and III, with attendant sliding of its pierced end 41 along the lever 38 toward the fulcrum 39 of the latter. The effective pressure of the link 42 upon the lever 38 and in turn upon the roller arm 35, is thereby decreased so that the arm 35 will rise from the dot and dash line position to the full line position in Fig. I with attendant anti-clockwise movement of the rock shaft 28. As a consequence, the angle of diversion of the yarn Y between the pig-tail guides 18, 19 is decreased and the pressure between the disks 21, 22 reduced through easement of the tension of the spring 26. It therefore follows that the restraint upon the yarn Y is gradually lessened from the beginning of the winding operation until the package C on the spindle 6 attains its maximum size, or in other words, the drag on the yarn is compensatively varied inversely with the increase in linear speed so that a constant effective tension is maintained to insure uniform winding and distribution of the yarn on the package C. During winding, the eccentric weighted disk 46 acts

to stabilize the device against spasmodic operation. By virtue of provision of the various adjustments hereinbefore described, the device may obviously be set for winding yarns of different gages or weights or for predetermining any desired degree of tension.

50 It is to be understood that I do not consider myself limited to the precise details of construction herein illustrated and described since these are capable of modification within the scope of the appended claims.

85 Having thus described my invention, I claim:

1. A tensioning device for yarn winding machines, comprising a pair of opposing restraining members between which the yarn is passed enroute to the winding spindle of the machine; a spring influential upon the restraining members; a pair of spaced fixed guides for directing the yarn in its passage; means for angularly diverting the yarn between the fixed guides; and means responsive to increase in the diameter of the yarn package being wound to concurrently regulate the pressure of the spring and to actuate the diverting means aforesaid for change in the angle of diversion, thereby to vary the restraint imposed upon the yarn.

90 2. A tensioning device for yarn winding machines comprising a pair of opposing restraining members between which the yarn is passed enroute to the winding spindle of the machine; a spring influential upon the restraining members; a pair of spaced guides for directing the yarn in its passage; a rock shaft; a finger on said shaft constituting a movable abutment for the spring; an arm on said shaft having a projection in the interval between the guides aforesaid for angularly diverting the yarn; and means responsive to increase in the diameter of the yarn package being wound controlling movement of the shaft with attendant regulation of the spring aforesaid and actuation of the diverting arm, thereby to vary the restraint imposed on the yarn.

95 3. A tensioning device for yarn winding machines comprising a pair of opposing restraining members between which the yarn is passed enroute to the winding spindle of the machine; a spring influential upon the restraining members; a pair of spaced guides for directing the yarn in its passage; a transverse rock shaft; a finger on said shaft constituting a movable abutment for the spring; an arm fixed on said shaft and having a projection thereon in the interval between the guides aforesaid to angularly divert the yarn; a roller arm also fixed to the rock shaft; a freely pivoted lever bearing on the roller of the arm; a link pivotally connected to the swinging frame of the winding machine which is moved as the diameter of the yarn package being wound increases, said link having its end resting on the lever aforesaid with capacity for sliding therealong for controlling movement of the shaft aforesaid for regulation of the spring and actuation of the diverting arm, thereby to vary the restraint imposed on the yarn.

100 4. A tensioning device for yarn winding machines comprising a pair of opposing restraining members between which the yarn is passed enroute to the winding spindle of the machine; a spring influential upon the restraining members; a pair of spaced guides for directing the yarn in its passage; a transverse rock shaft; a finger on said shaft constituting a movable abutment for the spring; an arm fixed on said shaft and having a projection in the interval between the guides aforesaid to angularly divert the yarn;

- a roller arm also fixed to the rock shaft; a freely pivoted lever bearing on the roller of the arm; a link pivotally connected to the swinging frame of the winding machine which is moved as the 5 diameter of the yarn package being wound increases, said link resting on the lever aforesaid with capacity for sliding therealong to control movement of the shaft for regulation of the spring and actuation of the diverting arm, there- 10 by to vary the restraint imposed on the yarn; and a weight adjustable along the link. 5. A tensioning device for yarn winding machines, comprising a pair of opposing restraining members between which the yarn is passed en- 15 route to the winding spindle of the machine; a helical spring influential upon the restraining members; a pivoted adjustably extensible finger with an angularly bent end portion constituting a movable abutment for the spring; and 20 means responsive to increase in the diameter of the yarn package being wound for controlling movement of the finger to regulate the pressure of the spring and thereby vary the restraint imposed upon the yarn by the restraining members. 25 6. A tensioning device for yarn winding machines comprising a pair of opposing restraining members between which the yarn is passed enroute to the winding spindle of the machine; a spring influential upon the restraining members; 30 a pair of spaced guides for directing the yarn in its passage; a transverse rock shaft; a finger on said shaft constituting a movable abutment for the spring; an arm on said shaft with a projection in the interval between the guides aforesaid for 35 angularly diverting the yarn; means responsive to increase in the diameter of the yarn package being wound for controlling movement of the shaft with attendant regulation of the spring and actuation of the diverting arm to vary the restraint imposed on the yarn; and stabilizing 40 means to prevent spasmodic oscillations of the rock shaft. 7. A tensioning device for yarn winding machines comprising a pair of opposing restraining 45 members between which the yarn is passed enroute to the winding spindle of the machine; a spring influential upon the restraining members; a pair of spaced guides for directing the 50 yarn in its passage; a transverse rock shaft; a finger on said shaft constituting a movable abutment for the spring; an arm on said shaft with a projection thereon movable in the interval be- tween the guides aforesaid to angularly divert the yarn; means responsive to increase in the diameter of the yarn package being wound for controlling movement of the shaft with attendant regulation of the spring aforesaid and actuation of the diverting arm to vary the restraint imposed on the yarn; and adjustable means to limit the rocking movement of the shaft. 8. A tensioning device for yarn winding machines comprising a pair of opposing restraining members between which the yarn is passed enroute to the winding spindle of the machine; a spring influential upon the restraining members; a pair of spaced guides for directing the yarn in its passage; a transverse rock shaft; a finger on said shaft constituting a movable abutment for the spring; an arm on said shaft with a projection thereon extending into the interval between the guides aforesaid to angularly divert the yarn; means responsive to increase in the diameter of the yarn package being wound for controlling movement of the shaft with attendant regulation of the spring aforesaid and actuation of the diverting arm to vary the restraint imposed on the yarn; and a weight adjustable along the link. 9. A tensioning device for yarn winding machines comprising a pair of opposing restraining members between which the yarn is passed enroute to the winding spindle of the machine; a spring influential upon the restraining members; a pair of spaced guides for directing the yarn in its passage; a transverse rock shaft; a finger on said shaft constituting a movable abutment for the spring; an arm fixed on said shaft and having a projection to engage and angularly divert the yarn in the interval between the guides aforesaid; a roller arm also fixed to the rock shaft; a freely pivoted lever resting on the roller of the roller arm; a link pivotally connected to the swinging frame of the winding machine which moves as the diameter of the yarn package being wound increases, said link resting in turn upon the lever aforesaid with capacity for sliding therealong for controlling movement of the shaft for regulation of the spring and actuation of the diverting arm to vary the restraint imposed on the yarn; and an eccentric disk weight adjustably set on the shaft to stabilize the device against spasmodic operation.
